UNITED STATES PATENT OFFICE

2,427,705

PIN SETTING MACHINE

Louis E. Blum, Jr., Newark, N. J., assignor to
 Breeze Corporations, Inc., Newark, N. J., a corporation of New Jersey

Application March 18, 1944, Serial No. 527,379

5 Claims. (Cl. 1—47)

1

This invention relates to mechanisms for uniting terminals to electric conductor wires, particularly such as are enclosed with a protective sheath.

An object of the invention is to provide a simple, pedally operated machine capable of inserting a wedge-like plug into a collar, through which the wires extend, to maintain them firmly therein, the collar then serving as a wire terminal.

A further feature is in the provision of means for semi-automatically adjusting the collars, into accurate registration with a revoluble head, carrying the plugs, and also drivers, in alternate relation to seat the plugs.

Another purpose is to produce a machine of such simplicity as to be easily operated by unskilled labor, in an effective, speedy manner whereby the assembly of parts are accurately accomplished.

These and other similar objects are attained by the novel construction, combination and arrangement of parts hereinafter described and shown in the annexed drawings, forming a graphical component of this disclosure, and in which:

Figure 1 is a perspective view of a complete embodiment of the apparatus.

Figure 2 is a top plan view of the same, partially in section.

Figure 3 is a front elevational view of the same in a downward position, partially in section, and illustrating its application.

Figure 4 is a perspective view of the revoluble head carried by the press, drawn to an enlarged scale.

Figure 5 is an enlarged transverse sectional view taken on line 5—5 of Figure 3, showing the head in a raised position.

Figure 6 is a longitudinal sectional view of a terminal lead assembly showing the work performed by the press.

Figure 7 is a transverse sectional view taken on line 7—7 of Figure 6, drawn to an enlarged scale.

Figure 8 is a sectional view of a modified pin holding die.

By reference to the drawings it will be seen that the mechanism includes a common type of pedally operated bench press, consisting of a base 15, adapted to be secured upon a bench, having a raised, forwardly reaching arm 16 terminating in an expanded head 17 extending over the base.

The head is recessed vertically to slidably re-

2

ceive a plunger or ram 18, of rectangular cross section, held in place by a cap 19, and provided with a rack 20 engaged by a spur gear 21, fixed on the end of a shaft 22, journalled in the head and extending laterally outward at the rear where it has secured on it a cylindrical hub 23.

Passing through the hub is a bar 24 having connected at its front portion a clevis 25, from which extends a rod 26 leading to a foot lever (not shown) below the bench; the opposite, upwardly bent rear portion 24' of the bar has attached to it a coiled tension spring 27 by which the plunger 18 is normally maintained in a raised position, the opposite end of the spring 15 being engaged in an adjustable screw 28 set in a bracket 29 carried by the base 15. A stop bar 30, set in the arm 16, limits the upward motion of the plunger.

A bracket 31, fixed on the upper end of the plunger 18, carries an adjustable stop screw 32, which, upon contact with the upper surface of the head 17, limits the downward movement of the plunger.

The structure described in the foregoing is well known and recited merely in order that a comprehensive understanding of the invention be had.

The lower end of the plunger 18 is bored axially to receive the shank 33 of a forked bearing 34 in which is rotatably mounted a transverse spindle 35, having fixed on its front extremity a knurled knob 36 and on its opposite end a disc 37 having equally spaced notches 38 adapted for engagement by a spring detent 39 carried by the upper part of the bearing.

Keyed to the central portion of the spindle 35, between the forks of the bearing 34, is a circular, non-magnetic wheel 40 having in its periphery an even number of radial, evenly spaced sockets 41, six being shown, in correspondence with the notches in the disc 37.

Set in each alternate socket is a magnet 42, and having an axial aperture 43, while in each intermediate socket is a similar flat faced driver die 44. In the modification shown in Figure 8, the die 42 is not magnetized but provided with an elastic collar 57, as rubber, having a small opening to receive the shank of the pin 54 with sufficient tension to retain it in position for insertion 50 in the bushing 53.

Secured on the raised forwardly extending portion of the base 15 is a plate 45 having a narrow extension 46 reaching beyond the edge of the base and provided with an open recess 47 55 in register with the plunger 18.

Rigidly fixed on the plate is a bracket 48 having, in its raised upper portion, a V-shaped guide notch 49 adapted to aline a work-part with the dies carried by the wheel 40.

The work, as indicated in Figures 3, 6, 7 and 8, consists of a cable 50 having a plurality of wires 51 and fitted with an insulating terminal 52, provided at its outer end with an opening suited to receive and retain a flanged metallic bushing 53, through which the wires pass to be secured thereover, at their bent ends, as by a wedge-like, hard steel pin 54 having a sharply tapered point 55.

In operation, a flanged collar 56 is loosely drawn over the cable (see Figures 3 and 5), below the cable terminal 52, to rest on the plate 45-46, in the recess 49, the terminal being further guided and alined by the angular notch 49, to register with the dies in the revoluble wheel 40.

Steel pins 54 are inserted in the magnets 42 with their points outward, the pins being retained by magnetism. Upon the first downward stroke 15 of the plunger, a pin is entered sufficiently into the bushing 53 to be retained by friction upright therein.

The second operation is to turn the wheel 40, bringing one of the driver dies 44 into position to set the pin, and then, by action of the press treadle, force it into the bushing, thereby clamping the wires therein, as indicated in Figure 7, allow the wheel carrying plunger to rise, remove the cable with its attached terminal and repeat the performance as required.

It is found in practice advisable to group the several wires at one side of the bushing 53 and bend their projecting ends sharply outward, as indicated in Figure 6, previously to the insertion of the pin.

Although the foregoing is descriptive of a specific purpose, it will be understood that the invention is not so confined, as it is apparent many other uses of a similar nature can be accomplished by the mechanism included in the appended claims.

Having thus described the invention and set forth the manner of its construction and use, what is claimed as new and sought to be secured by Letters Patent of the United States is:

1. In mechanism for setting pins in apertured elements, a reciprocably slideable, rotatable wheel having holding means to carry pins and partially drive them, means to rotate said wheel to a position to fully drive said pins, means intermediate said holding means to fully drive the pins, and means to locate the elements in position to receive the pins.

2. In mechanism for setting pins in apertured elements, the combination with a press having a base and a reciprocable plunger, a forked bearing fixed in the bottom of said plunger, a transverse spindle having means for rotation in said bearing, a wheel fixed on said spindle, magnetized dies set in spaced apart relation in the periphery

of said wheel to hold and partially drive said pins, means to rotate said wheel to a position to fully drive said pins, driver dies intermediate of said first named dies to fully drive the pins, and means on said base to register the elements with the axes of said dies.

3. In combination with a stamp press having a base, a plunger, and means to actuate the plunger, a work-part positioning device on said base, a non-magnetizable wheel rotatable in a vertical plane on said plunger, said wheel having radial peripheral sockets equally spaced there-around, a magnetic die set in each alternate socket adapted to engage a pin and partially drive said pin, driver dies set in the intermediate sockets to fully force such pin into the work-part, a knob to turn said wheel, a star wheel corresponding to the first named wheel, and a spring detent to engage said star wheel.

4. In combination with a stamp press having a base, a plunger, and means to actuate the plunger, means on said base to locate a work-part in register with the plunger, wheel of non-magnetic material mounted for rotation in said plunger, an even number of uniformly spaced radial sockets formed in the periphery of said wheel, means to rotate the wheel to bring any selected socket into alinement with a work-part on said base, a magnetized die fixed in each alternate socket to maintain a pin therein until partially entered in the work-part, and driver dies fixed in the intermediate sockets to fully force the pin into its final position in the work-part.

5. In mechanism for setting pins in apertured elements, the combination of a rotatable wheel having a plurality of spaced apart apertures, resilient means on the wheel provided with apertures aligned with said spaced apertures, said resilient means being arranged to grip and retain pins inserted into said spaced apertures until partially driven into the work-part, means to rotate said wheel to a position to fully drive said pins, means intermediate said spaced apertures adapted to fully drive the pins, means to locate the elements in position to receive the pins, means for supporting the wheel for rotation and means to reciprocate said supporting means.
